Specification for Design.

Patented Feb. 7, 1922.

Application filed May 2, 1921. Serial No. 466,234. Term of patent 7 years.

To all whom it may concern:

Be it known that I, FRANK YOKEL, a citizen of the United States, residing at Hartford, in the county of Hartford and State of Connecticut, have invented a new, original, and ornamental Design for a Lighting Fixture, (Case A, No. 11,250,) of which the following is a specification, reference being had to the accompanying drawing, forming part thereof.

Fig. 1 is a side elevation;

Fig. 2 is a central vertical section of the lower portion of the fixture; and
Fig. 3 is a bottom plan view.

I claim:

The ornamental design for a lighting fixture as shown.

FRANK YOKEL.
